UNITED STATES PATENT OFFICE.

SPECIFICATION forming part of Design No. 13,089, dated July 25, 1882.

Application filed June 10, 1882. Term of patent 3½ years.

To all whom it may concern:

Be it known that I, ARTHUR S. HALLIDAY, of Yonkers, in the county of Westchester and State of New York, have invented a new and original Design for Carpets, of which the following is a specification.

This invention relates to a new and original design for carpets and similar fabrics; and it consists in the novel grouping and configuration of parts hereinafter more fully described.

The accompanying photograph illustrates a face view of a carpet having my new design.

A is a stripe ornamented with the cross-band *a*, consisting of a double band of rectangular figures, resembling the rectangular Greek pattern; also with a band, *b*, consisting of a series of pendent rectangular figures, with blank spaces between them, hanging below a series of rectangular figures set alongside each other.

20 The stripe A is bordered by the band *f*, ornamented with a series of circular flower-like figures.

The stripe B contains the figure E, consisting of widely-open roses, above which projects the cluster *e* of leaves, branches, and foliage, the whole forming a sort of bouquet, of which the roses are the central portion. This bouquet E is bordered on each side by the figure *d*, resembling a pillar of trellis-work, consisting of a series of diamond-shaped figures placed between two upright posts.

The figure D consists of a widely-open rose-like flower above, and from which projects the leafy branch *c*.

The figure F is a band composed of a series 35 of arches with ornamentation between the pillars thereof.

I claim—

1. The design for carpets, consisting of the stripe A, containing bands *a b f*, substantially 40 as shown.

2. The design for carpets, consisting of the bands *a b*, substantially as shown.

3. The design for carpets, consisting of the figures E and *e*, substantially as shown. 45

7. The design for carpets, consisting of the stripe B, containing figures E, *e*, *d*, D, and *e*, substantially as shown.
